DESIGN FOR A METALLIC FLOWER HOLDER OR SIMILAR ARTICLE

Abraham Cooperstein, Brooklyn, N. Y.

Application August 17, 1934, Serial No. 52,976

Term of patent 7 years

To all whom it may concern:

Be it known that I, Abraham Cooperstein, a citizen of the United States, residing at 3452 Bedford Avenue, Brooklyn, in the county of Kings and State of New York, have invented a new, original, and ornamental Design for a Metallic Flower Holder or Similar Article, of which the following is a specification, reference being had to the accompanying drawing, forming a part thereof, which is a perspective front view of the metallic flower holder or similar article showing my new design.

The design is characterized by the inclusion of a center piece in the bulb.

I claim:

The ornamental design for a metallic flower holder or similar article, as shown and described.

ABRAHAM COOPERSTEIN.
